UNITED STATES PATENT OFFICE

CHARLES STERN, OF JERSEY CITY, NEW JERSEY, DE LANCEY W. DAVIS, OF SAYRE, PENNSYLVANIA, AND HENRY C. GILLESPIE, OF HUNTINGTON, WEST VIRGINIA, ASSIGNORS TO ARDCO MANUFACTURING COMPANY, OF HOBOKEN, NEW JERSEY, A CORPORATION OF DELAWARE

RAIL FLANGE LUBRICATOR

Application filed January 8, 1932. Serial No. 585,568.

The present invention relates to a combined rail and flange lubricator adapted for application to the rails of a track adjacent curves particularly, so as to prevent wear and cutting of the rails and the wheel flanges about the curves.

Another object of the present invention is to provide an improved structure of automatic operating means for the feed of the lubricant and which will insure the positive and complete operation of the means irrespective of the amount of depression to which the tread member is subjected during the passage of the wheels of rolling stock over the track to which the lubricator is applied.

Another object of the present invention is to provide a lubricant supply tank which is of such construction that the operating means thereof embodies an indicator visible from the exterior of the tank to determine without opening the tank the quantity of lubricant contained therein.

A further object of the present invention is to provide an improved feed plate construction and clamping or retaining plate therefor wherein the clamping plate communicates through the feed plate with a lubricant chamber and is provided with an integral neck eliminating various connections heretofore employed and admitting of the neck of the feed plate with a source of lubricant under pressure which is exposed beyond the adjacent base flange of the rail.

The invention further aims at the provision of certain improved constructions in the mounting of the intermittently operable devices for simplifying the construction of the same and providing a device which is strong, durable, relatively light in weight and which may be quickly and easily applied to a rail.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a fragmentary top plan view of a railroad track having a lubricating device constructed according to the present invention applied thereto.

Figure 2 is an enlarged fragmentary side elevation of the outer face of a rail having the lubricating device applied thereto.

Figure 3 is a transverse section taken on the line 3—3 of Figure 2, and showing a wheel of rolling stock in position on the rail and engaging the lubricating device.

Figure 4 is a top plan view of the lubricating device applied to a rail, parts being broken away for the sake of clearness.

Figure 5 is a detail vertical section taken through a lubricant supply tank, showing the feeding mechanism connected thereto.

Figure 6 is a fragmentary sectional view of a portion of the upper end of the supply tank, showing the combined outlet nozzle and closure plate therefor.

Figure 7 is a transverse section taken through the lubricating device on the line 7—7 of Figure 4 and showing the friction retaining means for the feed shaft.

Figure 8 is a fragmentary inner side elevation of a rail, showing the feeding and spreading means for supplying lubricant to the rail head.

Figure 9 is a fragmentary outer side elevation of a rail having a modified form of the lubricating device applied thereto, and

Figure 10 is a transverse section taken through the same on the line 10—10 of Figure 9.

Referring now to the drawings, and first to Figure 1, 15 designates the rails of a railroad track which are supported upon ties 16 in the usual manner. At one side of the track, which may be at the approach of a curve, or other desired location at which the lubricant is to be applied, there is provided in the road bed a pit or box 17 in which is placed a lubricant supply tank 18 and from which lubricant is adapted to be fed by an operating shaft 19 through a supply pipe 20 which leads to the track and beneath the adjacent rail 15 and is connected to a feed plate 21 secured to the inner side of the rail. The operating shaft 19 is intermittent.

ly turned through a suitable operating mechanism 22 which is actuated by a depressible shoe or member 23 supported on the adjacent rail in the path of a wheel 24, shown in Figure 3, by the rolling stock so that each time a wheel 24 passes over the shoe 23 a supply of lubricant is fed to the inner side of the rail head.

Each rail is of conventional form and comprises a base or body part supporting an upright web 25 which carries a head 26 on its upper edge over which the wheel 24 passes.

The lubricating device comprises an inner side plate 27 and an outer side plate 28. As shown to advantage in Figures 2, 3 and 4, the plates 27 and 28 are clamped against the opposite sides of the web 25 of the rail by bolts 29 with their nuts 30 which engage transversely through the web 25 and the plates. The plate 27 which is disposed at the inner side of the rail web is provided intermediate its ends and between its upper and lower edges with a depression or chamber 31 which is closed at its outer side by a feed plate 32 which not only extends throughout the length and height of the chamber 31 but sufficiently beyond the same to close the chamber and which rises above the plate 27 into a position at the side and adjacent the tread surface of the head 26 of the rail, as clearly shown in Figures 3 and 8. The feed plate 32 is provided in its inner face and at its upper edge portion with a plurality of flat slots 33 which open at their lower ends into the chamber 31 and at their upper ends open through the upper edge of the plate and against the adjacent side of the rail head 26. The feed plate 32 is provided with a central aperture 34 which registers with a registering aperture provided in a clamping plate 35. The clamping plate 35 engages over the feed plate and may be provided with a suitable packing as shown for sealing the clamp about the opening 34 in the feed plate. The clamp plate 35 is secured to the side plate 27 by a plurality of bolts 36, or the like, which may also pass through the feed plate 32 for binding the latter against the side plate 27 and holding the clamping plate against the feed plate.

The feed plate 32 is provided at an intermediate point with a supply neck 37 which may be cast integral with the clamping plate and which opens through the clamping plate in register with the aperture 34 so as to supply lubricant to the chamber 31. The neck 37 opens downwardly and is internally threaded to receive an elbow 38 to which is connected the supply pipe 20.

The supply pipe 20 leads from the lubricant supply tank 18, and as shown particularly in Figures 4, 5 and 6, the top of the tank 18 is provided with a closure plate 39 secured thereto by bolts 40, or the like, and which has an outwardly tapering supply

connection 41 as a part of the plate 39 and to the reduced end of which is connected the pipe 20. The tank 18 may be of any suitable construction but in the present instance is shown, in Figure 5, as comprising a pair of opposite end sections which are clamped or secured together by means of bolts 42 which are secured through out-turned flanges at the abutting ends of the tank sections.

The packing ring 43 may be used for sealing the sections in closed position.

A piston follower 44 is mounted to slide lengthwise in the tank 18 and is held from turning therein by means of a pair of guide rods 45 and 46 which are disposed in parallel relation and extend throughout the length of the tank 18. The guide rods 45 and 46 pass through suitably formed openings in the piston follower 44 and are offset from the axis of the piston to hold the latter from turning.

A screw rod 47 is disposed axially within the tank 18 and is mounted at its lower or inner end in a thrust bearing 48 carried in the lower head of the tank. The rod 47 engages in threaded relation through the piston follower 44 for feeding the same lengthwise in the tank when the rod 47 is turned. The upper or outer end of the screw rod 47 has bearing in the upper or outer head of the tank and extends therethrough and is provided upon its outer extremity with a non-circular projection 49 adapted to detachably receive thereon a crank handle, or the like by means of which the screw rod 47 may be manually turned in either direction.

For automatically operating the screw rod 47 and effecting the movement of the follower 44, the outer end of the rod 47 is provided with a worm wheel 50 which meshes with a worm 51 the shaft of which is mounted in a bearing bracket 52 and which has one end pivotally mounted upon a bolt 53, or the like, as shown in Figure 5, disposed to hold the worm 51 against the wheel 50 when the bracket 52 is swung inwardly to normal position as shown in Figure 4. The free end of the bracket 52 extends to the peripheral portion of the outer head of the tank 18 and is provided at its outer end and at its side remote from the wheel 50 with a notch 54 adapted to receive therein a latch lever 55 which is arranged at one side of the tank 18 and which extends outwardly therefrom for engagement with the bracket 52. The lever 55 is provided with a pair of spaced projections 56 adapted to lie against the upper and lower faces of the bracket 52 to hold the latter from swinging outwardly from the head of the tank 18.

The latch lever 55 is pivotally mounted at its inner or lower end upon a bolt 57 and is slidably engaged upon a spaced bolt or pin 58 which carries a spring 59 held by a nut 60 under tension against the outer side of the latch lever 55 to hold the latter

inwardly against the side of the tank 18 and in the path of the outer end of the bracket 52.

The latch lever 55 extends upwardly a sufficient distance to provide a hand hold by means of which the latch lever 55 may be swung outwardly against the tension of the spring 59 to release the bracket 52 when it is desired to swing the bracket and move the worm 51 away from the wheel 50.

The shaft of the worm 51 is connected by a suitable universal joint 61 to the operating shaft 19, and the latter may be adjusted as to length by means of a sleeve coupling 62 for accommodating the shaft 19 to the distance between the adjacent rail 15 and the tank 18. The inner end of the shaft 19 is connected by a second universal joint 63 to a spindle 64 mounted and headed in a bushing 65 which is carried by the outer side plate 28, as shown in Figure 3. Mounted to turn on the bushing 65 is a drum or rocker 66 cupped at its outer side and closed by a cap 67 which telescopes over the outer end of the drum or rocker 66. Keyed to the spindle 64 is a roller disc 68 adapted to turn the spindle and which is provided, as shown in Figure 2, at suitably spaced points in its periphery with shouldered and inclined slots 69 in which are mounted rollers 70, or the like, and the latter may be spring cushioned in the usual manner at the shouldered or inner ends of the slots. Surrounding the roller disc 68 is a clutch ring 71 which is engaged with a forced or tight fit into the copper side of the drum or rocker 66 so as to turn therewith. The rollers 70 are held from endwise displacement by a disc washer 72, or the like, mounted on the spindle 64 and held in place by a nut 65, as shown in Figure 3.

Outwardly of the cover cap 67, the adjacent member of the universal coupling 63 is mounted in a strap bearing 73 having a friction brake lining 74 engaging the joint member 63 for retarding the rotation of the drive or operating shaft 19 and to also hold the shaft against over-running. The strap bearing 73 has a cap piece or strap 75 through which pass bolts 76, the latter passing through the lower ends of a supporting bracket 77 and carrying springs 78 adjustably tensioned against the bracket 77 by nuts 79, or the like. The bolts 76 are thus placed under tension so as to yieldingly hold the cap piece or strap 75 against the friction lining 74. Thus, the tension on the shaft 19 may be adjusted.

The bracket 77 is substantially U-shape, as shown in Figures 1 and 4, and at its opposite ends is secured beneath the nuts 30 of the clamping bolts 29 which hold the side plates 27 and 28 to the rail.

The drum of rocker 66 is provided at one side with U-shaped arms or projections 80, and as shown in Figures 2 and 4. The closure cap 67 is cut out on one side to fit over

the outer arm or projection 80 when it is placed in position, thus preventing closure cap 67 from rotating on rocker 66. A pin 81 engages through the arms 80 and through the lower portion of link 83. The link 83 extends upwardly and is pivotally connected by means of a bracket 84 to the under side of a tread spring or shoe 85 disposed at the outer side of the rail head 26, as shown to advantage in Figure 3. One end of the spring 85 is pivoted upon a laterally extending bolt 86 preferably mounted upon the outer side plate 28 adjacent one end thereof. The other end of the spring 85 is connected by means of a shackle 87 to the other end portion of the plate 28 by means of a pivot bolt 88 which projects outwardly from the plate. Thus, the shackle 87 admits of the free spreading of the ends of the spring 85 when the intermediate portion thereof is depressed, and the movement of the intermediate portion of the spring, through the link 83 actuates the rocker 66.

The feed pipe 20 which extends from the outlet nozzle and enclosure plate 41 to the feed plate 35 preferably has a length of flexible hose therein so as to absorb vibration of the track during the passage of rolling stock thereover and to prevent any damage to the pipe couplings or joints. This vibration is also absorbed through the universal joints in the operating or drive shaft 19.

As may be observed from Figures 9 and 10, the improvements of the present invention may be applied to the pawl and ratchet type of feed. In this modification the spindle 64 carries a ratchet disc or wheel 89 which is keyed to the spindle and provided with ratchet teeth in its periphery. The rocker or drum 66 carries therein a plurality of pawls 90 for engagement with the ratchet disc 89 to intermittently turn the latter during the rocking of the drum or rocker 66. Chains 91 anchored at each end of plate 28 to underside of tread spring or shoe 85 is a safety feature should tread spring or shoe 85 break, thus holding same from getting on top of rail head 26.

The tank shown is adapted to be placed vertically in the pit or box 17, and to facilitate filling of the tank, the latter is provided with a vent pipe 92 which extends upwardly to the desired height in the box or pit 17, and which also admits of the free movement of the follower 44 upwardly or downwardly without any pressure against the under side thereof. The follower 44 is provided at its upper or outer side with a cushion spring 93 adapted to engage the outer end of the tank 18 for holding the follower in a downwardly urged position against the outer end of the threaded portion of the rod 47. The threaded portion of the head terminates at a point spaced from the outer end of the tank so that when the supply of lubricant is practically ex-

hausted from the tank the follower 44 will not be fed upwardly by the rod 47 even though the latter be continued in operation. As soon as the rod 47 is turned in a reverse direction, the follower 44 will be immediately forced on to the threads by the spring 43. The guide rod 45 which extends lengthwise in the tank 18 is mounted at the inner end of the tank upon a thrust bearing 94 and has a longitudinal spiral shoulder 95 cooperating with a key 96 mounted in the follower 44 so that as the follower 44 moves lengthwise in the tank or cylinder, the rod 45 is turned proportionately. The outer end of the rod 45 projects through the outer head of the tank or cylinder and has thereon an indicating arm 97 which traverses a dial or segment 98 fixed upon the upper end of the cylinder and which is suitably graduated to show the relative height of the follower 44 in the tank or cylinder. Thus, inspection may be made as to the quantity of lubricant in the tank 18 by merely observing the position of the pointer 97 without actually opening the tank. From Figure 2 particularly, it will be noted that the rocker member 66 is provided with a stop lug 98 which projects from the rocker member preferably at a point opposite from the arm 80 and which is disposed in line with an adjustable stop pin 99 mounted upon a projection 100 extending from the side of the plate 28 so as to limit the backward turning of the rocking member 66 when the spring 85 is raised. The stop 99 is adapted to take up lost motion or wear between the spring 85 and the rocking member when the two elements are disposed in their respective normal position of rest. Stop pin 99 screws into projection 100 and is provided with a lock nut at its lower end, as shown in Figure 2. The object of stop pin 99 is for raising or lowering tread spring or shoe 85 so as to regulate the rocking of rocker 66 and this in turn controls the revolutions of driving shaft 19 through worm 51 and worm wheel 50 to screw 47 which controls the amount of lubricant necessary. In operation, when a wheel of rolling stock passes over the adjacent rail head 26 and engages and depresses the spring shoe 85, the link 83 is forced downwardly and turns the rocker or drum 66 in one direction. This direction of movement of the rocker is preferably the power stroke and the slots 69 and the rollers 70 are so relatively positioned between the disc 68 and the ring 71 as to turn the spindle 64 and the operating shaft 19 during this depression of the spring 85. The shaft 19 turns the worm 51, worm wheel 50 and the threaded shaft or rod 47 in the tank 18. The direction in which the rod 47 turns under these conditions raises the follower 44 and forces the lubricant in the tank upwardly out of the tapering coupling 41 and into the feed pipe 20. The lubricant passes through the pipe 20 to the feed plate 35 by

means of the integral neck 37. The grease is thus fed under pressure to the chamber 31, and is caused to pass upwardly against the inner side of the feed plate through the slots 33 in the upper extention of the intermediate feed plate 32. The grease is thus distributed over a substantial area at the inner side of the rail head 26.

Any inherent resiliency of the spring tread 85 returns it to normal raised position and, through the link 83 turns the rocking member or drum 66 back to normal position and without turning the operating shaft 19 backwardly. The shaft 19 is yieldingly held in its forwardly turned position by means of the friction brake in the bearing 73. The shaft 19 is thus intermittently turned to intermittently feed the lubricant to the rail head so that the feeding of the lubricant depends upon the number of wheels 24 which pass over the particular portion of the rail 15 to which the lubricator is applied. It will be noted from Figure 3 that the neck 37 extends outwardly and downwardly from the plate 35 so that the feed pipe 20 may be connected to the neck 37 at a point beyond the adjacent base flange of the rail. Thus, the feed pipe or hose 20 may extend across the under side of the rail between, the ties or the like, and be connected by the elbow 38 directly to the lower outer end of the neck 37.

As the quantity of lubricant in the tank 18 decreases, the follower piston 44 rises and turns the indicator rod 45 so that the arm 97 moves over the fixed dial 98 and consequently shows at the exterior of the tank 18 the quantity of lubricant which is contained therein.

When it is desired to replenish the supply of lubricant in the tank 18, it is only necessary to grasp the upper end of the latch lever 55 and spring the same outwardly against the tension of the spring 59 to release the bracket 52. The bracket 52 is now swung outwardly from the worm wheel 50 to disengage the worm 51 therefrom. A crank handle, or other suitable tool may now be applied to the upper end 49 of the screw rod or shaft 47 and by means of which the latter is turned in a reverse direction to move the follower 49 downwardly in the tank. The cover plate 39 is now removed and the lubricant is placed in the tank. The flexible hose section in the pipe 20 admits of this free movement of the plate 39 so that the latter may be merely shifted to one side or raised out of the way for filling the tank. As shown in Figure 6, the cover plate 39 may be provided with a packing gasket and the like, to seal the plate on the tank 18.

Of course the tank 18 may be disposed in any other position than as shown in order to accommodate the tank to various conditions of the road bed and at any other easy point of access to the feed plate and the intermittent operating mechanism.

It is obvious that various changes and modifications may be made in the details of construction and design of the above specifically described embodiment of this invention without departing from the spirit thereof, such changes and modifications being restricted only by the scope of the following claims.

What is claimed is:

1. In a rail flange lubricator, a side plate for attachment to a rail, a spindle mounted on the side plate having a disc thereon with inclined slots in its periphery, rollers mounted in said slots, a rocking member mounted on said side plate, a ring secured in the locking member and encircling the disc for interlocking engagement with the rollers when the locking member is turned in one direction, a cap carried by the rocking member and enclosing the disc and rollers therein, a resilient depressible member carried by the side plate and connected to the rocking member and adapted for engagement with the wheels of rolling stock to turn said rocking member, and a friction brake operable on said spindle to yeldingly hold the same against backward movement upon the return rotation of the rocking member to normal position.
2. In a rail flange lubricator, a side plate adapted to be secured against the side of a rail beneath the head thereof and having a cavity in its outer side, a feed plate fitting against the side plate over said cavity and

having spaced channels in its upper edge portion projecting above the side plate, and opening into said cavity and for contact with the side of the head of the rail, a clamp plate secured over the feed plate and having an outwardly extending hollow neck opening through the clamp and feed plates into said cavity, and lubricant supply means connected to said neck.

3. In a rail flange lubricator, a side plate adapted to be secured against the side of a rail beneath the head thereof and having a lubricant chamber therein opening through the outer side of the plate, a thin feed plate fitting against the side plate over the cavity to close the same and having on its inner side spaced channels leading from the cavity through the upper edge of the feed plate to deposit lubricant against the side of the rail head and having an opening therethrough in register with the cavity, and a clamp plate secured against the feed plate to hold it to the side plate and having an integral neck opening through the clamp plate in register with the opening in the feed plate and extending downwardly and outwardly from the clamp plate for connection with a source of lubricant under pressure at a point beyond the rail base.

In testimony whereof we affix our signatures.

CHARLES STERN.
